CLAIM

The ornamental design for a capacitor module as shown and described.

DESCRIPTION

FIG. 1 is a top perspective view of a capacitor module, showing the new design;

FIG. 2 is a front view thereof;

FIG. 3 is a rear view thereof;

FIG. 4 is a left view thereof;

FIG. 5 is a right view thereof;

FIG. 6 is a plan view thereof;

FIG. 7 is a bottom view thereof;

FIG. 8 is a bottom perspective view thereof;

FIG. 9 is an enlarged view of portion "9" thereof shown in FIG. 1;

FIG. 10 is an enlarged view of portion "10" thereof shown in FIG. 1;

FIG. 11 is an enlarged view of portion "11" thereof shown in FIG. 4; and,

FIG. 12 is an enlarged view of portion "12" thereof shown in FIG. 8.

The dot-dot-dash broken lines depict the bounds of the enlargements and form no part of the claimed design.

The "LS" lettering and icon forming part of the claimed design is a registered trademark of LS Materials Co. Ltd.
